UNITED STATES PATENT OFFICE.

JOHN SCHUMACHER, SR., OF LOS ANGELES, CALIFORNIA.

ТИЛТИНГ ТРЕЙ.

Application filed November 25, 1921. Serial No. 517,624.

This invention relates to tilting trays for use in holding, transferring and handling slabs or sheets of wall board, plaster board or other material in the process of making, 5 finishing or otherwise disposing of the same, and it has for its object to provide means of the character stated which will be generally superior in relative simplicity and inexpensiveness of construction, taken in connection with durability, inherent strength, 10 convenience and facility in use and manipulation and operation, compactness in form and general efficiency and serviceability.

With the above and other objects in view, 15 the invention consists in the novel and useful provision, relative arrangement, combination, association and inter-relation and construction of parts, members and features, all as hereinafter described, shown in the 20 drawings, and finally pointed out in claims.

In the drawings:

Figure 1 is a side elevation of the tilting tray in its entirety;

Figure 2 is a plan view of a ledge member utilized in practicing the invention;

Figure 3 is a perspective view of upright members or supporting members used for supporting the tray member;

Figure 4 is an end view of the member shown in Figure 1 with the frame member in horizontal position;

Figure 5 is a view similar to Figure 4, with the frame member tilted; and,

Figure 6 is a fragmentary perspective view 35 of a portion of the frame member carrying arbors and a locking arm.

Corresponding parts in all the figures are designated by the same reference characters.

Referring with particularity to the drawings, the improved tilting tray is designated in its entirety by A, of which 1 is a tray member, 2 supports between the tray member and a carriage member 3, all of which elements are used in practicing one embodiment of the invention. The carriage member 3 may include the usual spaced flanged wheels 4 joined by an axle 5, which wheels are adapted to ride upon a track 6. Obviously the carriage member might be some form of truck and the wheels 4 do not of necessity have to be flanged. A frame member 7 is carried upon the axles 5, as shown in Figure 4, and there is a front and rear carriage 3 between which an I beam 8 extends, which I beam is supported upon the frame member 7 in each case and bolted or

otherwise held to said frame members 7. The uprights 2 are supported upon the beam 8 as shown in the figures, and said uprights are provided with two depending spaced members 9 and 10, which straddle the beam 8. A transverse plate 11 is adapted to rest on the top of the beam 8 and to be fastened thereto by means of bolts 12 passing through perforations 13 in the uprights 2. The depending members 9 and 10 are likewise provided with aligned perforations 14 and a bolt is adapted to pass through said perforations and the perforations in the beam 8 to securely hold the upright members to the beam as shown at 15. The supporting means comprise two pairs of supports 2, one pair being adjacent each end of the tray member, and the supports of each pair being separated each from the other. The supports 2 are provided at one end with bearing grooves 16. The tray member 1 which includes a frame 17 as well as the tray 18 proper, is so mounted upon the uprights 2 that the frame with its tray may be tilted into position as illustrated in Figure 5. In particular the frame member comprises two spaced longitudinal members 19 and 20 with cross pieces 21 joining said members 19 and 20. There are two cross pieces 21 and they are received within the space between each pair of supports 2. The cross pieces are shown in Figure 6, and it is to be observed that they are channeled in order to give strength to said pieces. A strap member 22 is carried at an intermediate portion of the cross pieces and said strap member in turn carries arbors 23 and 24. Said arbors are conveniently held to the strap 22 as by means of U-bolts 25. To aid in preventing crushing of the strap member 22 small supports 26 are interposed between the cross pieces 21 and the straps 22. The ends of said cross pieces are provided with upstanding clips 27 and the members 19 and 20 are adapted to be received between said clips 27 and rest upon a surface of the same, as best shown in Figure 4. A base member 28 is joined to the members 19 and 20 and corner pieces 29 are provided between the members 19 and 28 and 20 and 28 to give rigidity to the structure. Bolted to the member 20 are upstanding members 30 and the edge rail 31 shown in Figure 2 is adapted to be slipped over said members 30 as indicated in dotted line in Figure 1. The edge rail comprises two spaced members 32 and 33 having the

usual spacer blocks 34 and said edge rail operates in conjunction with the base 28 to prevent articles such as a wall board carried on said base from sliding from said base when the frame is tipped into the position illustrated in Figure 5. When the frame member considered as an entirety is placed upon the supports 2, the arbors 23 and 24 will be received within the bearing grooves 16, and as a consequence a pull upon one end of the frame will cause a tilting action of the frame with respect to the carriage, as well as the uprights 2. A locking means 35 is provided which is received in the space 15 between each pair of supports 2. This locking means 35 includes an arm member pivotally joined to the members 21 as shown at 36, with a portion of said locking means provided with a nose 37 and with an angularly directed extremity 38. When the frame is in a horizontal position, as illustrated in Figure 4, the angular extremity of the locking member 35 will engage an edge of the I beam 8. A pull upon the arm 25 35 will tilt the frame into the position shown in Figure 5 so that the nose 37 may engage an edge of the I beam 8 as shown at 39. The frame in its tilting action will contact with the frame member 7 and limit further rotation or tilting of the frame. The wall board may then be easily removed from the tray, whereupon the locking arms 35 may be released and the frame again assume a horizontal position as illustrated in Figure 4. 30 Quite obviously the left-hand side of the frame might be provided with an edge rail and further locking arms 35, so as to allow the frame to tilt to either side.

It is obvious that many changes and modifications may be made in practicing the invention in departure from the particular showing, all, however, without departing from the true spirit of the invention and the scope of the appended claims.

Having thus disclosed my invention, I claim and desire to secure by Letters Patent:

1. Apparatus of the character disclosed, comprising a tray member upon which material is adapted to be supported, and supporting means for said tray member; said supporting means including separate pivotal supports respectively disposed eccentrically of the tray member, whereby the tray member may be supported in one position by both of said supports, and supported in another and tilted position by one of said supports; said supporting means including uprights and said tray member having arbors revolvably received by said uprights, and means for locking the tray member either in substantially horizontal or in tilted position; said tray member comprising a frame and a tray provided with an edge rail to maintain the material in position upon the tray when the tray is in tilted position; said tray when the tray is in tilted position; said

uprights being spaced apart and each comprising two members, and said means for releasably locking said tray being disposed between the members of said uprights.

2. Apparatus of the character disclosed, comprising a tray member upon which material is adapted to be supported, and supporting means for said tray member; said supporting means including separate pivotal supports respectively disposed eccentrically of the tray member, whereby the tray member may be supported in one position by both of said supports, and supported in another and tilted position by one of said supports; said supporting means including uprights and said tray member having arbors revolvably received by said uprights, and means for locking the tray member either in substantially horizontal or in tilted position; said tray member comprising a frame and a tray provided with an edge rail to maintain the material in position upon the tray when the tray is in tilted position; said uprights being spaced apart and each comprising two members, and said means for releasably locking said tray being disposed between the members of said supports; said uprights being connected by a beam with which said locking means cooperates.

3. Apparatus of the character disclosed, comprising a tray member upon which material is adapted to be supported, and supporting means for said tray member; said supporting means including separate pivotal supports respectively disposed eccentrically of the tray member, whereby the tray member may be supported in one position by both of said supports, and supported in another and tilted position by one of said supports; said supporting means including uprights and said tray member having arbors revolvably received by said uprights, and means for locking the tray member either in substantially horizontal or in tilted position; said tray member comprising a frame and a tray provided with an edge rail to maintain the material in position upon the tray when the tray is in tilted position; said uprights being spaced apart and each comprising two members, and said means for locking said tray being disposed between the members of said uprights; said uprights being connected by a beam with which said locking means cooperates; said locking means comprising a locking arm provided with locking noses for engaging said beam.

4. Apparatus of the character disclosed, comprising a tray member upon which material is adapted to be supported, and supporting means for said tray member; said supporting means including separate pivotal supports respectively disposed eccentrically of the tray member, whereby the tray member may be supported in one position by both of said supports, and supported in an-

other and tilted position by one of said supports; means being provided for limiting the tilting movement of said tray member in one direction, and a further means being provided for locking said tray in each of two positions assumed by it; said last named means comprising a lever carried by the

tray member and adapted to engage with certain of the supporting means for said tray member.

10

In testimony whereof, I have signed my name to this specification.

JOHN SCHUMACHER, Sr.
